ELECTRIC SOLDERING IRON

Charles Thomas Beadling, Canonsburg, Pa.

Application January 13, 1937, Serial No. 120,446

1 Claim. (Cl. 219—26)

The present invention relates to new and useful improvements in electric soldering irons and has for its primary object to provide, in a manner as hereinafter set forth, a tool of this character embodying a novel construction, combination and arrangement of parts through the medium of which the handle will be prevented from getting hot when the device is in use.

Other objects of the invention are to provide a soldering iron of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view principally in side elevation of an electric soldering iron constructed in accordance with the present invention, a portion of the handle being broken away in longitudinal section.

Figure 2 is a view in vertical longitudinal section through the tool, a portion only of the handle being shown.

Figure 3 is a cross sectional view, taken substantially on the line 3—3 of Fig. 1.

Figure 4 is a cross sectional view, taken substantially on the line 4—4 of Fig. 1.

Figure 5 is a detail view in elevation of the tubular element container.

Figure 6 is a detail view in vertical longitudinal section through the plug which is mounted in one end portion of the tubular element container.

Referring now to the drawings in detail, it will be seen that the embodiment of the invention which has been illustrated comprises a handle 1 of suitable material. Mounted in one end portion of the handle 1 and projecting longitudinally therefrom is a tube 2 of suitable metal having ventilating openings or perforations 3 therein. The handle 1 is provided with a longitudinal bore 4 which communicates with the perforated tube 2. The perforated tube 2 is substantially filled with a suitable heat insulating material 5 such as asbestos wool. The asbestos wool 5 is loosely packed to facilitate the circulation of air therethrough.

Threadedly mounted in the forward end portion of the perforated tube 2 is a tubular container 6 of suitable metal. Threadedly mounted on the forward end portion of the tubular container 6 is a copper tip 7. Mounted in the tubu-

lar container 6 is an electric heating element 8 which is provided with rearwardly extending leads 9.

Threadedly mounted in the rear end portion of the tubular container 6 is a plug 10 through which the leads 9 pass, as illustrated to advantage in Fig. 6 of the drawings. The plug 10 is insulated, as at 11. The reference numeral 12 designates conductor wires which are connected to the leads 9 at the rear end of the plug 10, as at 13. The conductor wires 12 pass through the asbestos wool 5 in the perforated tube 2 and through the bore 4 in the handle 1 for connection with a suitable source of current through the medium of a conventional plug (not shown).

In use, the plug 10 retains most of the heat from the element 8 in the tubular container 6, preventing said heat from escaping at the rear end of said tubular container thereby promoting the efficiency of the tool. The heat insulating material 5, such as asbestos wool, further prevents heat from the element 8 and the tubular container 6 from being transmitted to the handle 1. Further, the circulation of air through the perforations 3 and the medium 5 materially assists in maintaining the handle 1 in a cool condition. It will be observed that the tubular element container 6 is internally and externally threaded on its rear end portion for engagement in the perforated tube 2 and to accommodate the plug 10.

It is believed that the many advantages of an electric soldering iron constructed in accordance with the present invention will be readily understood and although a preferred embodiment of the tool is as illustrated and described, it is to be understood that changes in the details of construction and in the combination and arrangement of parts may be resorted to which will fall within the scope of the invention as claimed.

What is claimed is:—

An electric soldering iron comprising a handle, a perforated tube having one end mounted in one end of the handle, a tubular container having internal and external threads at one end thereof and the outer end of the perforated tube being internally threaded to receive the external threads of said container, a plug in said end of the container and engaging the internal threads, a tip threaded to the outer end of the container, an electric heating element in the container, leads connected with the element and passing through the plug, conductors connected with the leads and passing through the perforated tube and the handle and heat insulating material in the perforated tube.

CHARLES THOMAS BEADLING.
